United States Patent Office.

WILLIAM H. BONNELL, OF BUFFALO, NEW YORK.

Letters Patent No. 96,772, dated November 16, 1869.

LANTERN.

The Schedule referred to in these Letters Patent and making part of the same.

I, WILLIAM H. BONNELL, of Buffalo, in the county of Erie, and State of New York, have invented certain "Improvements in Lanterns," of which the following is a specification.

The nature of my invention consists in constructing the globe-protecting wire frame of a lantern, so that the wire applied, running horizontally with the lantern, will pass through the wire, running vertical, or the whole to be reversed, thus securing a very strong and comparatively cheap wire frame, which construction may also be applied to many other purposes, such as muzzles, &c.; also in providing a lantern with a deflecting-base.

I refer to the drawing, which illustrates the invention more fully, and which makes part of this specification. It represents the lantern in a side view, a portion of deflector being cut out in order to show the operation of the same.

Letter A is the wire frame; it is constructed of two wire rings, each of which is provided with six holes. These holes are made by first splitting the wire at the respective places, and then sufficiently opening the same so that the wires running in contrary direction may be passed through said holes, in which they are to be secured with soft solder.

B is the glass globe; it is secured within the wire frame resting at the lamp and the deflecting-base C.

C is this deflecting-base; it is secured to the wire frame A, as can be seen by the drawing; the top of

the deflector being open, and of sufficient size, so that the lower portion of the globe B will fit within it. The light which is transmitted through the lower portion of the globe, within the opening of C, is deflected by means of the reflecting power of C, and, as the rays of light are reflected by the well-known optical law, it can be observed that in a certain distance the rays are brought to a focus, and, therefore, no shadow of the body of the lamp can occur, and the much-desired feature of a lantern (the throwing down of light directly beneath the lantern) is obtained.

D is the top of the lantern, and is secured to the top wire ring of wire frame A, by means of a hinge and a spring-catch, d, for the purpose of taking out the globe at the top of the lantern.

Claims.

Having thus fully described my invention, What I desire to secure by Letters Patent, is—

1. Constructing and securing together wires of wire frames by passing one wire through the other, substantially as and for the purposes specified.

2. In combination with a lantern, the deflecting-base C, to be constructed and to operate substantially as described and set forth.

W. H. BONNELL.
